UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Continuation of application Serial No. 592,444, filed October 4, 1922. This application filed December 29, 1922. Serial No. 609,723.

To all whom it may concern:

Be it known that I, RONALD A. McCANN, a citizen of the United States, residing at Swissvale, in the county of Allegheny and 5 State of Pennsylvania, have invented certain new and useful Improvements in Railway-Traffic-Controlling Apparatus, of which the following is a specification.

My invention relates to railway traffic 10 controlling apparatus of the type wherein traffic governing means located on a railway car or train is controlled by energy received from the trackway. More particularly, my invention relates to apparatus of this character for use on single track railways over 15 which traffic moves in both directions and which are provided with passing sidings.

In systems of the type referred to, means 20 are usually provided for giving one indication or another on a train approaching a siding when the block beyond the siding is occupied, the indication depending on whether the train in the block beyond the siding is moving towards or away from the 25 siding. One feature of my invention is the provision of novel and improved means for preventing a change from a higher speed indication to a lower speed indication aboard the train, due to a train entering the block 30 ahead, when the first train is approaching the siding under a proceed signal indication.

The present application is a continuation 35 of my co-pending application filed on the 4th day of October, 1922, Serial No. 592,444, for railway traffic controlling apparatus, in so far as the subject-matter common to the two is concerned, the said co-pending application being a renewal of my application 40 filed on the 28th day of May, 1920, Serial No. 384,830.

I will describe one form of apparatus embodying my invention, and will then point out the novel features thereof in claims.

45 In the accompanying drawings, Fig. 1 is a view showing a stretch of railway track provided with roadside signals controlled in accordance with one usual and well known method. Figs. 2 and 2^a, when placed end to 50 end in the order named, constitute a diagrammatic view showing one arrangement of apparatus embodying my invention and adapted for use in conjunction with the

roadside signal arrangement shown in Fig. 1.

Similar reference characters refer to similar parts in each of the several views.

Referring first to Fig. 1, the reference characters 2 and 2^a designate the track rails of a stretch of single track over which traffic moves in both directions. The stretch shown in the drawing comprises two blocks A—D and E—H, separated by a passing siding N. Traffic through block E—H from east to west is governed by a plurality of signals S', S^a and S^b, located at intervals through the block, and traffic through the same block from west to east is governed by a similar set of signals S^c, S^d and S^e. Traffic through block A—D from east to west is 65 similarly governed by a set of signals S^o, S¹¹ and S¹³, while traffic through this block from west to east is governed by signals S¹⁶, S¹⁴ and S¹². Westbound traffic into the passing siding N is governed by a signal S⁷, 70 and eastbound traffic into this siding is governed by a signal S¹⁰. As here shown, each signal is of the three position type capable of giving three indications, namely, "proceed" when the semaphore arm is vertical, "caution" when the semaphore arm is inclined, and "stop" when the semaphore arm is horizontal. I do not desire, however, to limit myself to signals of this particular character.

The blocks A—D and E—H are divided by insulated joints 3, into a plurality of successive sections A—B, B—C, etc., and, as here shown, a pair of opposing signals is located at the junction of each two adjacent 90 sections. I do not wish, however, to be limited to this specific location of the signals.

The control of the signals, is as follows:

Normally all signals are in the proceed position, as shown in the drawing. When a train moving toward the east enters block A—B, signals S^o, S¹¹, S¹³ and S¹⁶ move to the stop position, signal S^o remaining at stop as long as the train occupies any part of the block. When the train passes out of section A—B, signal S¹⁶ moves to the caution position, and when the train passes out of section B—C this signal returns to the proceed position. Signal S¹⁴ moves to the stop position when the train enters section 100 B—C, and this signal returns to the caution 105

position when the train has passed out of this section. When the train enters section C—D, signal S^{12} moves to the stop position, and when the train passes out of section 5 C—D signal S^{12} returns to the caution position and signal S^{14} returns to the proceed position. Signal S^{10} , of course, moves to the stop position when the train enters section D—E, and it returns to caution when the 10 train passes point J in section E—F, at which time signal S^{12} returns to the proceed position. It follows, therefore, that two or more trains may pass through the block moving in the same direction under the 15 same signal protection as is customarily provided on double track roads. The operation of the signals during the movement of a westbound train through block A—D will be understood from the foregoing without 20 further explanation. The signals for block E—H are controlled in the same manner as the signals for block A—D.

The operation of the signals which I have just outlined may be accomplished by apparatus and circuits of various types. Several 25 such forms of apparatus and circuits are now known in the art, and, consequently, a detailed explanation of the means for controlling the signals is not considered necessary. A signaling system of the type described is commonly known as "absolute permissive signaling."

Whenever signal S^9 indicates stop, signal S^7 indicates caution, and whenever signal S^7 30 indicates stop, signal S^5 indicates caution. It is desirable, however, for reasons which are well understood in the art, that when an eastbound train occupies any part of the block A—D, signal S^5 , as well as signal S^7 , 35 should indicate caution, but that when a westbound train has passed point Q in section C—D, thus allowing signal S^7 to move to the caution position, signal S^5 should return to the proceed position. One method 40 of accomplishing this selective operation of signal S^5 will be explained hereinafter.

Referring now to Fig. 2, I have here 45 shown the portion of the track between points D and F, together with all of the apparatus and circuits associated therewith for accomplishing the objects of my invention. The track section D—E, which includes the passing siding N, is provided with a track circuit comprising a track battery b adjacent point E and a track delay T^{10} adjacent point D. The section E—F is divided into two sub-sections E—J and J—F, and each subsection is provided with a track circuit comprising a battery b and a track relay 50 designated T^8 or T^6 . The section to the west of point D is provided with a track circuit of which only the track relay T^9 is shown in the drawing, and similarly the section to the east of point F is provided with a track 55 circuit of which only the track relay T^6 is

shown in the drawing. The track battery b for each track circuit is connected across the rails in series with the secondary of a transformer designated by the reference character U with a suitable exponent, the functions of which transformers will be set forth hereinafter.

Each signal S is controlled by a signal relay which is designated by the reference character R with the same exponent as that of the corresponding signal. Considering signal S^7 , for example, the caution indication circuit is from terminal B of a suitable source of current through the front point of contact 4 of relay R^7 , wires 5 and 6, 75 operating mechanism of signal S^7 , wire 7 and contact 8 of relay R^7 to terminal C of the same source of current. The proceed indication circuit for this signal is from terminal B through the front point of contact 4, wires 5 and 9, polarized contact 10 of relay R^7 , wire 11, operating mechanism of signal S^7 , wire 7, and contact 8 to terminal C of the same source of current. It will be seen, therefore, that signal S^7 will indicate proceed when relay R^7 is energized in such direction that contact 10 is closed, which I will term the "normal" direction of energization, and that this signal will indicate caution when relay R^7 is energized in the other or "reverse" direction. Relay R^7 is energized in normal or reverse direction according as it is supplied with current of "normal" or "reverse" polarity.

The control of each signal by the corresponding signal relay R is similar to the control of signal S^7 just explained.

Signal relay R^9 is controlled by contact 12 of track relay T^9 and by other apparatus in the block A—D in such manner that this relay is de-energized when an eastbound train enters this block, but that this relay becomes energized in reverse direction after a westbound train passes signal S^{11} and in normal direction after a westbound train passes signal S^{13} .

Signal relay R^7 is provided with a circuit which passes from terminal B of a suitable source of current through pole-changer P^9 , wire 13, contact 14 of track relay T^9 , wire 15, contact 16 of track relay T^{10} , wire 17, winding of relay R^7 , common wire O' and pole-changer P^9 to terminal C of the same source of current. Pole-changer P^9 is operated by signal S^9 in such manner that current of normal polarity is supplied to relay R^7 when signal S^9 is in the proceed or caution position, but that current of reverse polarity is supplied to relay R^7 when signal S^9 is in the stop position. Relay R^7 is, of course, de-energized when either track relay T^9 or T^{10} is open.

Signal relay R^5 is controlled by a pole-changing relay K^7 , the circuit being from terminal B of a suitable source of current

through front point of contact 44 of relay K⁷, wire 45, contact 46 of track relay T⁸, wire 47, contact 48 of track relay T⁵, wire 48^a, winding of relay R⁵, common wire O², 5 wire 49, and front point of contact 50 of relay K⁷ to terminal C of the same source of current. The current which is thus supplied to relay R⁵ is of normal polarity, so that signal S⁵ indicates proceed. When relay 10 K⁷ is de-energized, the circuit for relay R⁵ is the same as before, except that the polarity of the current flowing therein is reversed, so that signal S⁵ will indicate caution. Relay R⁵ is, of course, de-energized 15 when either track relay T⁵ or T⁸ is open.

Relay K⁷ is provided with a circuit which passes from terminal B through pole-changer P⁹, wires 112 and 150, contact 20 operated by signal S⁹, wires 21 and 22, contact 23 operated by signal S⁷, wire 24, winding of relay K⁷, wire 25, and common wire O and pole-changer P⁹ to terminal C. This circuit is provided with a branch around contact 20 of signal S⁹, which branch 25 passes from wire 112 through wires 151 and 153, contact 29 of relay R⁹ and wires 30 and 28 to wire 22. The signal-operated contacts 20 and 23 are each closed when the corresponding signal indicates caution or 30 proceed, but not when it indicates stop. It follows that, in so far as the circuits which I have traced are concerned, relay K⁷ will be open whenever signal relay R⁹ is open, that is, whenever a train occupies section 35 C—D, and whenever an eastbound train occupies any portion of block A—D. The circuit for relay K⁷ is provided, however, with a second branch, around contacts 20 and 29, which branch passes from wire 112 40 through wires 151 and 152, contact 26 of an auxiliary relay L⁹, and wires 27 and 28 to wire 22. Relay L⁹ is provided with a pick-up circuit which passes from terminal B, through contact 35 operated by signal S⁹, wire 36, back contact 37 of track relay T⁹, wires 38 and 39, winding of relay L⁹, wire 40 and back contact 41 of signal relay R⁹ to terminal C. This circuit is closed when 45 a westbound train enters section C—D, because at that time contacts 37 and 41 become closed before contact 35 opens. The pick-up circuit for relay L⁹ is not closed, however, during the passage of an eastbound train along the track, because relay R⁹ is 50 opened by such a train before track relay T⁹ opens, and so contact 35 is open when contact 37 of track relay T⁹ becomes closed. Relay L⁹ is provided with a holding circuit which passes from battery terminal B, 55 through contact 42 of the relay itself, wires 43 and 39, winding of relay L⁹, wire 40 and back contact 41 of signal relay R⁹ to terminal C. It follows, therefore, that when auxiliary relay L⁹ is closed by a westbound 60 train it remains closed until signal relay R⁹

becomes energized, that is, until the rear of the train passes out of section C—D. It will be seen, therefore, that when an eastbound train enters block A—D, the opening of signal relay R⁹ and the consequent movement of signal S⁹ to the stop position cause the pole-changing relay K⁷ to become de-energized so that signal S⁵ moves to the caution position. When a westbound train passes along the track, however, relay K⁷ 70 becomes energized as soon as the train passes point Q in section C—D, due to the fact that stick relay L⁹ has been closed, so that signal S⁵ then returns to the proceed position. 80

Considering now the eastbound signals, signal relay R⁶ is controlled by contact 51 of track relay T⁶ and by suitable apparatus in sections F—G and G—H, so that this relay is opened when a westbound train enters block E—H. Signal relay R⁸ is provided with a circuit which passes from terminal B of a suitable source of current, through pole-changer P⁶ operated by signal S⁶, wires 52 and 53, contact 54 of relay R⁶, wires 55 and 56, contact 57 of track relay T⁵, wire 58, contact 59 of track relay T⁸, wire 59^a, winding of relay R⁸, common wire O², wire 60, and pole-changer P⁶ to terminal C of the same source of current. 90 This circuit is provided with a branch around contact 54 of relay R⁶, which branch passes from wire 52 through wires 61 and 62, contact 63 of auxiliary relay L⁶ and wire 64 to wire 56. Relay L⁶ is controlled by track relay T⁶, signal relay R⁶, and by signal S⁶, the circuits being substantially the same as the circuits for relay L⁹. The circuit for signal relay R¹⁰ is controlled by pole-changer P⁸, contact 18 of track relay T⁸, and contact 19 of track relay T¹⁰, the circuit being similar to the circuit for signal relay R⁷. Pole-changing relay K¹⁰, which controls signal S¹², (not shown in Fig. 2), is controlled by contact 31 of signal S⁸, and contact 32 of signal S¹⁰, the main circuit for this relay being similar to the circuit hereinbefore traced for pole-changing relay K⁷. The circuit for relay K¹⁰ is provided with a branch around signal-operated contact 31, including contact 33 of relay R⁸, and with a second branch which includes contact 34 of auxiliary relay L⁸. The circuits for relay L⁸ are similar 110 to the circuits for the corresponding relay L⁹. 115

When an eastbound train enters block A—D, it opens relay R⁹, thereby causing signal S⁹ to move to the stop position. The consequent reversal of pole-changer P⁹ 125 causes relay R⁷ to be energized in the reverse direction, so that signal S⁷ moves to the caution position. The opening of relay R⁹, together with the movement of signal S⁹ to the stop position opens the circuit for pole- 130

changing relay K^7 (relay L^9 being open), so that relay R^5 becomes energized in the reverse direction, thereby causing signal S^5 to move to the caution position. When such train enters the right hand sub-section of section C—D, the opening of track relay T^9 opens the circuit for relay R^7 , so that signal S^7 moves to the stop position. As the train enters section D—E, the opening of track relay T^{10} opens the circuit for relay R^{10} , so that signal S^{10} moves to the stop position, and when the entire train has passed point D, relay R^9 again closes, so that signal S^9 returns to the proceed position. As the train 10 enters sub-section E—J, the opening of track relay T^8 opens the circuit for relay R^5 , so that signal S^5 moves to the stop position, and the same track relay opens the circuit for relay R^8 so that signal S^8 moves to the 15 stop position. When the entire train passes out of section D—E, the consequent closing of track relay T^{10} permits relay R^7 to close, so that signal S^7 returns to the proceed position. When the train passes point J, 20 relay R^{10} closes in reverse direction so that signal S^{10} moves to the caution position. As the train passes point F signal S^6 moves to the stop position and signal S^5 returns to the proceed position. Signal S^8 also returns to the 25 caution position, so that signal S^{10} moves to the proceed position.

When a westbound train enters block E—H, it causes relay R^6 to open, so that signal S^6 moves to the stop position. The opening of relay R^6 causes relay R^8 to open, so that signal S^8 also moves to the stop position. The consequent operation of pole-changer P^8 causes relay R^{10} to become energized in the reverse direction, so that signal 30 S^{10} moves to the caution position. As the train enters sub-section J—F the opening of track relay T^5 opens the circuit for relay R^5 , so that signal S^5 moves to the stop position. The subsequent opening of track relay T^8 , 35 due to the entrance of the train into sub-section E—J opens the circuit of relay R^{10} , so that signal S^{10} moves to the stop position. When the train enters section D—E, the opening of track relay T^{10} opens relay R^7 40 so that signal S^7 moves to the stop position. The consequent opening of contact 23, operated by signal S^7 , opens the circuit for relay K^7 so that when the entire train has 45 passed out of section E—F signal S^5 returns only to the caution position. As the train passes point D auxiliary relay L^9 becomes closed. The passage of the train into the first sub-section of section C—D does not permit relay R^7 to close, because this relay is 50 controlled by track relay T^9 . After the train leaves the first sub-section to the left of point D, however, track relay T^9 closes so that relay R^7 then becomes energized in reverse direction and signal S^7 moves to the 55 caution position. The circuit for relay K^7 60

is then closed at contact 23 and contact 26, so that this relay then becomes energized; this causes signal relay R^5 to be energized in the normal direction so that signal S^5 returns to the proceed position. 70

Each section of track is provided with means for supplying alternating vehicle governing current to the rails of the section at both ends. Considering section D—E, for example, this current is supplied to the battery end through the medium of a transformer U^2 , the secondary of which is included in the track circuit between the battery b and the upper track rail 2, and the primary of which is at times supplied with alternating current as explained hereinafter. At the relay end of this track section the vehicle governing current is furnished by a transformer U^2 , the secondary of which is connected across the rails of the section in 80 multiple with the track relay T^{10} . A resistance 124 is included between the secondary of transformer U^2 and one track rail to prevent the transformer from forming a low resistance shunt across the track relay T^{10} . 90 Each track section or sub-section is supplied with vehicle governing current in substantially the same manner as section D—E. 95

The supply of vehicle governing current to the transformers U is controlled in the following manner: Considering transformer U^2 for section D—E, the primary winding of this transformer is directly connected with the secondary of a transformer V^3 , and the primary of transformer V^3 is at times connected with transmission mains 65 and 66 to which alternating current is constantly supplied by a generator W. The circuit for the primary of transformer V^3 is from transmission main 65, through wires 67 and 68, contact 70—69, wire 71, contact 72—73, wire 74, primary of transformer V^3 and wire 75 to transmission main 66. It will be seen that this circuit is closed only when signal S^7 is at stop and signal S^8 is in the proceed or caution position. In other words, vehicle governing current is supplied to the rails at the right-hand end of section D—E only when a train moving toward the east is approaching signal S^8 and section E—F is unoccupied. 110

The circuit for the primary of transformer U^2 is from transmission main 65, through wires 76 and 77, contact 78—79, wire 80, contact 82—81, wire 83, primary of transformer U^2 and wires 84^a and 84 to transmission main 66. This circuit is closed only when signal S^{10} is at stop and signal S^9 is in the caution or proceed position; in other words, vehicle governing current is supplied to the rails at the left-hand end of section D—E only when a westbound train is approaching signal S^9 and section C—D is unoccupied. 120

Considering now section E—F, the circuit 125

for the primary of transformer U^6 is from transmission main 65, through wires 85 and 86, contact 87-88, wire 89, contact 90-91, wires 92 and 93, primary of transformer U^6 5 and wire 94 to transmission main 66. The circuit for the primary of transformer U^4 is the same as the circuit for the primary of transformer U^6 up to and including wire 92, and it then passes through wire 95, primary 10 of transformer U^4 and wire 96 to transmission main 66. It will be seen, therefore, that transformers U^4 and U^6 are energized only when signal S^5 is at stop and signal S^6 is in the caution or proceed position; that is, only 15 when a train moving toward the east is approaching signal S^6 and the section F-G is unoccupied.

The normal circuit for the primary of transformer U^8 is from transmission main 20 65, through wires 67 and 97, contact 98-72, wire 71, contact 69-99, wires 100 and 101, contact 102 of pole-changing relay K^7 , wires 103, 104 and 105, primary of transformer U^8 25 and wires 106 and 75 to transmission main 66. The circuit for the primary of transformer U^5 is the same as the circuit just traced up to and including wire 104, and it then passes through wire 107, primary of transformer U^6 , wire 108 and wire 96 to transmission main 30 66. It will be seen from the foregoing that transformers U^5 and U^8 are normally energized only when signal S^8 is at stop and signal S^7 is in the caution or proceed position and pole-changing relay K^7 35 is energized. The circuits for transformers U^8 and U^5 are provided, however, with a branch around contact 102 of relay K^7 , which branch passes from wire 100 through wire 109, contact 110 of an auxiliary relay 40 M^7 , and wire 111 to wire 104. When relay M^7 is closed, then, transformers U^5 and U^8 will be energized regardless of the condition of relay K^7 , provided that signals S^7 and S^8 are in the positions specified above.

45 Relay M^7 is provided with a pick-up circuit which passes from terminal B^2 of a suitable source of current through contact 113 of auxiliary relay L^5 , wire 114, wire 115, contact 116, wire 117, winding of relay M^7 , wire 118, and common wire O^2 to terminal C^2 of the same source of current. It follows 50 that relay M^7 will be energized when relay L^5 is closed and signal S^7 is in the proceed position, that is, it will close when a west-bound train passes signal S^8 provided that signal S^7 is then in the proceed position. Relay M^7 is provided with a holding circuit which passes from terminal B^2 , through contact 113, wires 114 and 119, contact 120 of 55 signal relay R^7 , wire 121, contact 122 of relay M^7 , wire 123, winding of relay M^7 , wire 118, and common wire O^2 to terminal C^2 . It follows that when relay M^7 is once 60 energized by a westbound train it will remain closed until such train enters section 65

D-E, even though relay K^7 may open while the train is in section E-F.

It is understood that the trackway apparatus shown in Fig. 2 is arranged for co-operation with suitable vehicle-carried apparatus which operates to give a proceed indication on a vehicle when the vehicle occupies a section of track to which alternating vehicle governing current is supplied to the rails in advance of the vehicle, and a stop indication when the vehicle occupies a section to which such current is not supplied. One form of vehicle governing apparatus of this nature is described and claimed in an application filed by Lloyd V. Lewis 70 on August 15, 1919, Serial No. 317,830, for railway traffic controlling apparatus.

I will now assume that a westbound train equipped with apparatus of the character specified, passes along the track. As this 75 train enters sub-section J-F, it causes relay M^7 to close. Transformers U^5 and U^8 are then supplied with alternating current independently of the contact 102 of pole-changing relay K^7 . While this train is in either 80 sub-section J-F or E-J, if an eastbound train should enter block A-D, the consequent opening of pole-changing relay K^7 would not cause the vehicle governing apparatus on the westbound train to change to a 85 stop indication. If, however, the eastbound train should get into sub-section Q-D while the westbound train is still in section E-F, the consequent opening of track relay T^9 would open the circuit of relay R^7 and contact 90 120 of the latter relay would open the stick circuit for relay M^7 so that the apparatus on the westbound train would then give a stop indication.

95 One important feature of my invention 100 is the fact that I accomplish the control just explained by means of an auxiliary stick relay M^7 , thereby eliminating the necessity for providing the pole-changing relay K^7 with a stick circuit. This feature is an advantage when, as in the present disclosure, relay K^7 is included in the circuit with a pole-changer so that this relay is at times energized by current of one polarity and at other times by current of the other polarity 105 110 as it is not always desirable to apply a stick circuit to a relay which is controlled in this manner.

Another important feature of my invention 115 is the fact that normally the circuits for the primaries of the transformers U are open, these circuits being closed only while a train is approaching and passing through the corresponding section of track. It follows, therefore, that there is no unnecessary 120 consumption of energy from the alternating current generator W .

125 Although I have herein shown and described only one form of apparatus embodying my invention, it is understood that varying 130

ous changes and modifications may be made therein within the scope of the appended claims without departing from the spirit and scope of my invention.

5 Having thus described my invention, what I claim is:

1. In combination, a stretch of railway track comprising two blocks separated by a 10 passing siding, the first block being provided with a track section adjacent said siding, a signal for governing traffic through said section towards the siding, a relay for controlling said signal, means for opening said relay when a train enters the second block 15 moving towards the siding, a second relay, means for holding said second relay closed while a train moving towards said siding occupies said section even though a second train moving in the opposite direction 20 subsequently enters said second block, and means controlled by said second relay when closed for supplying vehicle governing current to said section.

2. In combination, a stretch of railway 25 track comprising two blocks separated by a passing siding, the first block being provided with a track section adjacent said siding, a signal for governing traffic through said section towards the siding, a relay for controlling said signal, means for opening said relay when a train enters the second block 30 moving towards the siding, a second relay, a pick-up circuit for said second relay including a contact closed when the siding and the second block are unoccupied, a holding circuit for said second relay including 35 a contact of the relay itself and a contact which is open only when a train is in or adjacent the siding, and means controlled by said second relay when closed for 40 supplying vehicle governing current to said section.

3. In combination, a stretch of railway 45 track comprising two blocks separated by a passing siding, the first block being provided with a track section adjacent said siding, a signal governing traffic through said section towards said siding, a relay for controlling said signal, means for opening said relay when a train enters the second block 50 moving towards said siding, a second relay, means for holding said second relay closed while a train moving towards said siding occupies said track section, even though a second train moving in the opposite direction 55 subsequently enters said second block, means controlled by said first relay when closed for supplying vehicle governing current to said section, and means controlled by said 60 second relay when closed for supplying vehicle governing current to said section independently of the first relay.

4. In combination, a stretch of railway track comprising two blocks separated by a

passing siding, the first block being provided with a track section adjacent said siding, 65 a signal for governing traffic through said section towards the siding, a relay for controlling said signal, means for opening said relay when a train enters the second block 70 moving towards the siding, a second relay, means for closing said second relay when a train moving towards the siding enters said section provided the second block is not then occupied by a train moving towards the siding 75 and for subsequently holding the second relay closed until the train enters the siding even if a train moving in the opposite direction enters the second block in the meantime, and means controlled by said second 80 relay when closed for supplying vehicle governing current to said section.

5. Railway traffic controlling apparatus comprising a section of railway track, a track circuit for said section including a 85 source of direct current and a track relay, and means controlled by a train approaching said section for supplying vehicle governing alternating current to the rails of the section in series with said source of direct current.

6. Railway traffic controlling apparatus comprising a section of railway track, a track circuit for said section including a source of direct current and a track relay, a transformer whose secondary is included in the connection between one track rail and said source, and means controlled by a train approaching said section for supplying vehicle governing alternating current to the 100 primary of said transformer.

7. Railway traffic controlling apparatus comprising a section of railway track, a track circuit for said section including a source of direct current and a track relay, a transformer whose secondary is included in the connection between one track rail and said source, and means controlled by a train approaching said section for supplying vehicle governing alternating current to the 110 primary of said transformer when the track on the opposite side of said section is unoccupied.

8. Railway traffic controlling apparatus comprising a section of railway track, a track circuit for said section including a source of direct current and a track relay, and means controlled by a train approaching said section for supplying vehicle governing alternating current to the rails of the section in series with said source of direct current 115 when the track on the opposite side of said section is unoccupied.

9. Railway traffic controlling apparatus comprising a section of railway track over which traffic moves in both directions, and means controlled by a train approaching said section from either direction for connecting

a source of vehicle governing alternating current across the rails of the section at the opposite end of the section.

10. Railway traffic controlling apparatus comprising a section of railway track, a track circuit for said section including a source of direct current connected across the rails at one end of the section and a track relay connected across the rails at the other 5 end of the section, a transformer whose secondary is included in said track circuit between one track rail and said source of direct current, and means controlled by a train approaching said section and about to enter 10 the section at the track relay end for supplying alternating current to the primary of said transformer provided that the track on the opposite side of said section is unoccupied.
11. Railway traffic controlling apparatus comprising a section of railway track, a track circuit for said section including a source of direct current and a track relay, a roadside signal for said section controlled by 25 said track relay, and means controlled by a train approaching said section for connecting a source of vehicle governing alternating current across the rails of said section at the end farthest from the train.

12. Railway traffic controlling apparatus comprising a section of railway track, a track circuit for said section including a source of direct current, and a track relay, and means controlled by a train approaching 30 said section for connecting a source of vehicle governing alternating current across the rails of the section in multiple with said track relay.

13. Railway traffic controlling apparatus comprising a track divided into a plurality of successive sections, a track circuit for each section including a source of direct current and a track relay, signals for the sections controlled by said track relays, and means controlled by a train approaching each section for connecting a source of vehicle governing alternating current across the rails of the section at the end of the section farthest from the train provided that the next section 45 adjacent said latter end is unoccupied.

14. In combination, a stretch of railway track comprising two blocks separated by a passing siding, the first block being provided with a track section adjacent said siding, a signal for governing traffic through said section toward the siding, a relay for controlling said signal in such manner that when the section is unoccupied the signal indicates proceed or caution according as the relay is 50 energized or de-energized, means for de-energizing said relay when a train enters the second block moving toward the siding, a second relay, means for closing said second relay when a train moving toward the siding 55 enters said section provided the second block

is not then occupied by a train moving toward the siding and for subsequently holding the second relay energized until the train enters the siding even if a train moving in the opposite direction enters the second block 70 in the meantime, and means controlled by said second relay when energized for supplying vehicle governing current to said section.

15. In combination, a stretch of railway track comprising two blocks separated by a passing siding, the first block being provided with a track section adjacent said siding, a relay controlled by traffic conditions in the second block in such manner as to be closed 75 when the block is unoccupied and opened when a train enters the second block moving toward the siding, means controlled by said relay for supplying vehicle governing current to said track section, a second relay, means for closing said second relay when a train enters said section moving toward the siding and for subsequently holding it closed even if a second train moving in the opposite direction enters the second block, and means 80 for supplying vehicle governing current to said track section independently of said first relay when the second relay is closed.

16. In combination, a stretch of railway track comprising two blocks separated by a passing siding, the first block being provided with a track section adjacent said siding, a relay controlled by traffic conditions in the second block in such manner as to be closed when the block is unoccupied and when a train moving away from the siding has reached a given point in the second block but opened when a train enters the second block moving toward the siding, means controlled by said relay for supplying vehicle governing current to said track section, a second relay, means for closing said second relay when a train enters said section moving toward the siding and for subsequently holding it closed even if a second train moving in the opposite direction enters the second block, and means for supplying vehicle governing current to said track section independently of said first relay when the second relay is closed.

17. In combination, a stretch of railway track comprising two blocks separated by a passing siding, the first block being provided with a track section adjacent said siding, a relay controlled by traffic conditions in the second block in such manner as to be closed when the block is unoccupied and opened when a train enters the second block moving toward the siding, means for supplying vehicle governing current to said track section when a train occupies the section moving toward the siding if said relay is closed, a second relay, means for closing said second relay when a train enters said section moving toward the siding and

for subsequently holding it closed even if a second train moving in the opposite direction enters the second block, and means for supplying vehicle governing current to 5 said track section independently of said first relay when the second relay is closed.

18. In combination, a stretch of railway track comprising two blocks separated by a passing siding, the first block being provided with a track section adjacent said siding, means operating when a train moving toward the siding occupies said track section for supplying vehicle governing current to the track section if the second 15 block is unoccupied but not if the second block is occupied by a train moving toward the siding, a normally open stick relay functioning when closed to continue the supply of vehicle governing current to said 20 track section even if a train enters the second block moving toward the siding, and means for closing said relay when a train moving toward the siding enters said section provided the second block is not occupied by a train moving toward the sid- 25

ing and for subsequently holding the relay closed while the train is in the section even if a second train in the meantime enters the second block moving toward the siding.

19. In combination, a stretch of railway track comprising two blocks separated by a passing siding, the first block being provided with a track section adjacent said siding, a relay controlled by traffic conditions in the second block in such manner as to be closed when the block is unoccupied and opened when a train enters the second block moving toward the siding, a second relay, means for closing said second relay when a train enters said section moving toward the siding and for subsequently holding it closed even if a second train moving in the opposite direction enters the second block, and means controlled jointly by said two relays for supplying vehicle governing current to said track section. 30 35 40 45

In testimony whereof I affix my signature.

RONALD A. McCANN.
